(57) **CLAIM**

The ornamental design for a dynamic adjustable tension band, as shown and described.

DESCRIPTION

FIG. 1 is a perspective view of an dynamic adjustable tension band, showing my new design as fixed with a watch mechanism;

FIG. 2 is a top plan view thereof, illustrated in an extended configuration with the watch mechanism omitted for clarity;

FIG. 3 is a bottom plan view of FIG. 2;

FIG. 4 is a right-side elevational view of FIG. 2, the left-side elevational view being a mirror image thereof;

FIG. 5 is a front elevational view of FIG. 2; and,

FIG. 6 is a rear elevational view of FIG. 2.

The broken lines showing a watch mechanism in FIG. 1 depict environmental matter and form no part of the claimed design. The remaining broken lines represent stitching, and are part of the claimed design.
